Howard Mason

by Geo W. Goddard,
Atty.

UNITED STATES PATENT OFFICE.

HOWARD MASON, OF AMSTERDAM, NEW YORK, ASSIGNOR TO SHAWMUT ENGINEERING COMPANY, OF BOSTON, MASSACHUSETTS, A CORPORATION OF MASSACHUSETTS.

AXMINSTER TUBE FRAME.

Application filed July 19, 1922. Serial No. 575,973.

To all whom it may concern:

Be it known that I, HOWARD MASON, a citizen of the United States, residing at Amsterdam, in the county of Montgomery and State of New York, have invented new and useful Improvements in Axminster Tube Frames, of which the following is a specification.

Reference may be had to the accompanying drawings, and the reference characters marked thereon, which form a part of this specification. Similar characters refer to similar parts in the several figures therein.

This invention relates to tube-frames such as are used in weaving Axminster carpets or other pile-fabric.

A frame of this type comprises in general a rigid longitudinal carrier-bar adapted to carry the yarn-spool, and also to form a substantial support for the tubes which control and guide the delivery of the yarn to the fabric in the weaving operation.

Tube frames of this type are more or less frail in construction and are subject to many mishaps and smashes in the operation of the looms.

The principal object of the present invention is to provide a more substantial mounting of the tubes upon the carrier-bar and to facilitate repairs in case of a smash or accident to more or less of the tubes carried by the bar.

Other objects will appear in connection with the following description.

Fig. 1 of the drawings is a view in perspective of one of the angle-plates employed in my improved tube-frame.

Fig. 2 is a cross-section of the same.

Fig. 3 is a view in perspective showing the same with a number of tubes mounted thereupon applied to the carrier-bar.

Fig. 4 is a cross-section of the same.

Fig. 5 is a similar cross-section showing the carrier-bar in the form of a channel-iron.

Fig. 6 is a similar cross-section showing the carrier-bar made solid, and preferably of wood.

Fig. 7 is a view in front elevation of the tube-frame complete with the yarn-spools mounted thereupon.

Referring to Figs. 1, 2, 3 and 7 wherein the invention is shown in preferred form, 1 is the carrier-bar shown as a hollow rectangular member having the usual bearing brackets, 2-2, for the spools, 3, which carry the

yarn to be guided and fed to the fabric 55 through the tubes, 4, of the tube-frame.

Mounted upon the lower front portion of the carrier-bar, 1, are a plurality of angle-plates, each having a member, 5, extending along the front surface of the bar, and a member, 6, extending along the bottom surface of the bar, adjacent to the angular edge, formed at the junction of the front and bottom surfaces of the bar.

The member, 5, of each of these angle-plates has its upper edge retroverted as shown at 7, and made in the form of teeth, 8, which are spaced apart and with relation to the tubes, 4, in accordance with the character of work for which the tube-frame is to be 70 employed.

The tubes, 4, are mounted upon the respective angle-plates by resting upon the surface of the member, 5, and with the intake ends of the respective tubes interiorly engaged by 75 the teeth, 8.

The tubes, 4, are preferably secured in this position by a soldered connection, 9, along an intermediate portion of the tubes at the junction of the members, 5 and 6, of 80 the respective channel-irons.

Each tube is thus supported and braced or clamped at its intake end by one of the teeth, 8, inserted therewithin; and this engagement in connection with the soldered 85 connection, 9, described, combines the tubes with the angle-plate in a substantial rigid structure.

The member, 5, of each angle-plate is formed with a plurality of hooks, 10, engageable respectively with hook-openings, 11, formed in the front wall of the carrier-bar, 1; and the member, 6, of each angle-plate is formed with a plurality of screw-openings, 12, adapted to align with screw-threaded openings, 13, formed in the bottom wall of the carrier-bar, 1.

Each angle-plate is mounted upon the bar, 1, by inserting the hooks, 10, in the respective openings, 11, and then inserting screws, 14, through the respective screw-holes, 12, in the member, 6, of the angle-plate into the respective screw-threaded holes, 13, in the bottom wall of the bar.

The angle-iron having the members, 5 and 6, may be made in a single piece to support all of the tubes of the frame, or it may be made up of as many separate sections,

each supporting a number of tubes, as may be desired.

I am thus able to provide a light and substantially rigid support for the tubes; and by employing a plurality of angle-plates having the members, 5, 6, I avoid the necessity of removing all of the tubes in case of a smash or accident to certain only of the tubes.

16 Thus, if the damaged tubes are all located on a single angle-plate, that plate only need be removed for repair or replacement of the injured tubes.

18 By having the teeth, 8, extend interiorly of the intake ends of the respective tubes, a smooth inlet surface is formed by the teeth which facilitates the passage of the yarn through the tubes.

20 For certain purposes of the invention the carrier-bar may be made of any desired material and of any desired form. Thus, in Fig. 5, I have shown the bar in the form of a channel-iron, 1^a, this form permitting the construction to be otherwise the same as above described in connection with the bar, 1.

25 In Fig. 6, I have shown a solid wooden bar, 1^b, to the front side of which the angle-plates may be secured by screws, 15. Otherwise the construction is substantially as above described.

30 For certain purposes of the invention, the carrier-bar may be provided in any known manner with teeth, 8, having the functions above described.

35 What I claim as new and desire to secure by Letters Patent is—

1. A tube-carrying and attaching element for an Axminster tube frame, embracing in its construction a longitudinal tube-carrying strip provided along its upper edge with a series of exteriorly disposed tuft tube-engaging and spacing teeth and having also interiorly disposed hook-like members adapted to penetrate and interlock with the carrier-bar, substantially as described.

40 2. In an Axminster tube frame, the combination of a longitudinal carrier-bar, a tuft tube carrying and attaching member comprising a longitudinal strip provided along its upper edge with tube-spacing and engaging members and having rearwardly disposed bar-penetrating hook members, and fastening screws arranged to secure said strip against said carrier bar and prevent movement thereof permitting the withdrawal of the hooks from their receiving apertures in the carrier-bar, substantially as described.

45 3. An Axminster tube-frame having a carrier-bar, a tube-carrying and attaching toothed-plate removably secured to the carrier-bar, and tubes secured to the toothed-plate with their intake ends interiorly engaged by the respective teeth thereof.

4. A tuft-guiding element adapted to be secured to the carrier-bar of a tube-frame embracing in its construction a backing plate adapted to extend longitudinally of the carrier-bar, a plurality of parallel transversely disposed tuft tubes secured thereto, said plate having one of its longitudinal edges reversely bent and slotted to form individual teeth projecting into the intake ends of the tuft tubes and serving, when in use, to prevent the yarn from chafing against the end edges of the tuft tubes, substantially as described.

5. An Axminster tube-frame having a carrier-bar with angular edge-portion, an angle-plate mounted upon the angular edge-portion of the bar, said angle-plate having one of its edges retroverted and formed with teeth extending toward said angular edge of the bar, and tuft tubes secured to said angle-plate with their intake ends interiorly engaged by said teeth respectively.

6. An Axminster tube-frame having in combination a carrier-bar formed with an angular edge-portion and provided with hook-openings in a surface adjacent to said angular edge and with screw-threaded openings in a neighboring surface adjacent to said angular edge, an angle-plate mounted upon the angular edge-portion of the bar, one member of said angle-plate having its edge retroverted and formed with teeth extending toward said angular edge of the bar, and with hooks engageable with the respective hook-openings in the bar the other member of said angle-plate being provided with screw-openings alined with the respective screw-threaded openings in the bar; screws inserted through the respective screw-openings in the angle-plate into the screw-threaded openings in the bar; and tubes mounted upon said angle-plate with their intake ends interiorly engaged by the respective teeth thereof.

7. In an Axminster tube frame, the combination with a longitudinal carrier bar, a tube-carrying attaching strip arranged longitudinally thereof and secured thereto, a series of parallel transversely arranged tuft tubes secured to said attaching strip by soldered connection at points intermediate the ends of the tubes, said attaching strip having one of its longitudinal edges reversely folded and transversely slotted to form teeth projecting into the intake ends of the tubes in overlapping relation to the end edges of the back walls of the tubes, thereby accurately positioning and holding the tuft tubes while protecting the yarn from chafing as it enters the tubes.

8. An Axminster tube-frame having in combination a carrier-bar formed with an angular edge portion and provided with hook-openings in a surface adjacent to said angular edge and with screw-threaded open-

- ings in a neighboring surface adjacent to said angular edge; an angle-plate mounted upon the angular edge-portion of the bar, one member of said angle-plate having its 5 edge retroverted and formed with teeth extending toward said angular edge of the bar, and with hooks engageable with the respective hook-openings in the bar, the other member of said angle-plate being provided 10 with screw-openings alined with the respective screw-threaded openings in the bar; screws inserted through the respective screw-openings in the angle-plate into the screw-threaded openings in the bar; and tubes 15 mounted upon said angle-plate with their intake ends interiorly engaged by the respective teeth thereof.
9. An Axminster tube-frame having in combination a carrier-bar formed with an 20 angular edge-portion and provided with hook-openings in a surface adjacent to said angular edge, and with screw-threaded openings in a neighboring surface adjacent to said angular edge; a plurality of angle-plates each having one of its members formed 25 with hooks engageable respectively with the
- hook-openings in said bar, and having the edge of said member retroverted and formed with teeth extending toward the angular edge of the bar, the other member of each of 30 said angle-plates being provided with screw-openings in alinement respectively with said screw-threaded openings in the bar; screws inserted through the screw-threaded openings in the respective angle-plates into the screw-threaded openings in the bar; and tubes mounted upon the respective angle-plates with their inlet ends interiorly engaged by the respective teeth thereof. 35
10. In an Axminster tube frame, the combination with a longitudinal carrier-bar, of a longitudinal tube-attaching strip provided with inwardly turned bar-penetrating hooks arranged to hook into corresponding apertures formed in the bar, and fastening means applied to the exterior of the bar to prevent said hooks from withdrawal from 40 said apertures, substantially as described. 45

In testimony whereof I have hereunto set my hand this 12th day of July, 1922.

HOWARD MASON.
